THERMIONIC TUBE

Arsène N. Lucian, Philadelphia, Pa., assignor to
Heatless Light Corporation, a corporation of
Delaware

Application January 12, 1929, Serial No. 332,009

15 Claims. (Cl. 250—27.5)

My invention relates to electrical apparatus, having particular relation to thermionic tubes.

One object of my invention is to provide a simple, efficient and compact alternating-current tube, wherein the usual alternating-current hum is eliminated to an extent heretofore considered impossible.

Another object of my invention is to provide a tube having an equipotential cathode, heating means therefor, and a third electrode, and means whereby said third electrode may be shielded from said heating means.

Still another object of my invention is to provide a vacuum tube with means, whereby the electromagnetic interaction between the heating means and the plate or grid may be prevented, and the cathode maintained as a magnetic shield throughout its length.

A further object of my invention is to provide an equipotential cathode with means, whereby the plate or grid may be electrostatically shielded from the heating means.

A still further object of my invention is to provide apparatus of the character described, wherefore in the lead conductors and the heating filament for the equipotential cathode are shielded from the plate or grid substantially the entire length of said filament and conductors.

Other objects and applications of my invention, as well as details of construction and operation, whereby my invention may be practiced, will be apparent more fully hereinafter, when taken in connection with the accompanying drawing, wherein

35 Fig. 1 is a vertical, sectional view of a vacuum tube and its associated base member;

Fig. 2 is a bottom plan view of the vacuum tube base shown in Fig. 1;

40 Fig. 3 is an enlarged perspective view of one of the filament insulators shown in Fig. 1;

Fig. 4 is an enlarged detail vertical sectional view of an alternative embodiment of my invention;

45 Fig. 5 is a diagrammatic view of the heating means shown in Fig. 1 with its associated transformer;

Fig. 6 is a similar view, but showing the connection of the heating means of Fig. 4 to its transformer and to ground;

50 Fig. 7 is a detail view of the insulating tube with one portion thereof moulded around the lead conductors; and

Fig. 8 is an enlarged detail view of a portion of the device of Fig. 1; and

55 Fig. 9 is a detail view of a modification.

As a result of considerable development work, I have found that a large part of the hum in alternating-current vacuum tubes is due to the absence or the inadequacy of the electromagnetic and electrostatic shielding of the grid and plate from the heating means. One embodiment of my invention, which is particularly designed for complete and effective electromagnetic and electrostatic screening, is shown in Fig. 1, wherein a tube 1 is secured at a lower end 2 in a base member 3. The lower end portion 2 is provided with a re-entrant stem 4 which terminates at its upper end in a press 5.

One of the features of my invention is the molding in the press 5 a molded portion 6 (Fig. 7) of a glass stem 7, the stem 7 containing therein a pair of insulatingly-spaced lead wires or conductors 8 and 9. In practice, the conductors 8 and 9 are first placed in the stem 7 in spaced relation, whereupon a portion 6 is heated so as to cause the material to mold around the wires 8 and 9, securing them in insulatingly-spaced relation. The final step consists in placing the molded portion 6 in the upper end of the reentrant stem 4 and then molding the latter and the portion 6 of the stem 7 together, so as to form the composite press of Fig. 1.

As shown in Fig. 1, an end portion 11 of the stem 7 projects upwardly beyond the press 5 into the tube 1, constituting a physical shield for the lead wires 8 and 9. Upper ends 12 and 13 of these wires are connected to the lower ends of a filament 14, an upper end 15 of which is connected to a hook 16 supported in a small insulating block 17 of the character shown in Fig. 3. It is noted that the block 17 is provided with a plurality of longitudinal recesses 18, so that a plurality of relatively small surface portions 19 may engage an adjacent inner side 21 of a surrounding tubular member 22.

An insulating member 23 (Fig. 3) similar to the member 17 is positioned within a lower open end 24 of the tubular member 22 and it is provided with spaced apertures 25 and 26 through which the adjacent end portions of the filament 14 are threaded. The insulating member 23 is similarly provided with longitudinal recesses, so that surface contact between the member 23 and the tubular member 22 may be reduced to a minimum. Such relatively small insulating supporting members 17 and 23, with their minimum surface contact with the tubular member 22, permits a very great reduction in the electrical leakage between the filament 14 and the member 22.

The tubular member 22 is preferably formed of

magnetic material, and it is provided with an outer surface coating 28 so as to form an electron emitting equipotential cathode 29. A grid 31 and a plate 32 are so positioned as to surround the 5 cathode 29 and are connected by lead conductors 33 and 34 to external contact pins 35 and 36 extending outwardly from a lower side of the tube base 3.

In accordance with my invention, the passage 10 of electrostatic fields of force, as well as electromagnetic lines of force, through the upper end of the tubular member 22 is prevented by closing the same with a cap 37 of magnetic material. The 15 electro-magnetic lines of force extending from the cap 37 are now shunted through the member 22 to the lower end portion of the member 22. Moreover, the cap 37 serves to block the passage 20 of electrons between the filament 14 and the grid 31 and the plate 32, due to the electrostatic lines in a vacuum tube is eliminated.

My invention further contemplates the complete shielding of the lower open end of the tubular member 22. This desired result is obtained 25 by mounting a sleeve 38 of insulating material such as quartz, lavite, on the outer side of a lower edge portion 39 of the member 22 and extending the sleeve 38 over an upper edge portion 41 of the stem end portion 11, as shown in Fig. 1. Thus, the 30 lead wires 8 and 9, as well as the heating means 14, is mechanically shielded from the grid 31 and the plate 32, inasmuch as such electrons as tend to pass from the heating means 14 are blocked by the stem end portion 11 and the insulating sleeve 35 38. Accordingly, electrostatic shielding is provided for the lower open end portion of the tubular cathode 29.

The electromagnetic shielding of the lower end portion of the heating means 14, as well as the adjacent 40 portions of the lead conductors 8 and 9, is accomplished by mounting a sleeve 42 of metal or other magnetic material on the outer side of the quartz or lavite sleeve 34, the upper and lower ends of the sleeve 42 over-lapping the cathode 29 45 and the stem end portion 11, as shown in Fig. 1. The sleeve 42 is connected by a conductor 43 to the cathode 29 and the latter is grounded by means of a lead conductor 44 extending from a mid-point 45 in the cap 37 through the press 5 to a pin 46 mounted on the underside of the tube base 3. Added protection may be provided by 50 positioning a sleeve 47 within the stem end portion 11, so as to enclose the portion of the lead wires 8 and 9 between the press 5 and the filament 14. The sleeve 47 is grounded on the tubular cathode 29 by means of a conductor 48. Such construction affords a very complete electromagnetic as well as electrostatic shielding for the 55 lower open end of the cathode 29, preventing the establishment of a substantial static or magnetic field between the filament 14, the lead conductors 8 and 9 and the grid 31 and the plate 32. It is noted that the insulating sleeve 38 may be omitted and the space between the lower end of the 60 cathode 29 and the upper end of the stem 11 may be closed by the magnetic shielding member 42 alone, as shown clearly in Fig. 9.

A further source of hum in alternating current tubes is present in that portion of the lead 70 conductors 8 and 9 for the heating means 14 which is positioned in the base 3. This source is eliminated in my invention by providing the conductor 8 with a tubular section 49 which extends upwardly from a bottom wall of the base to a 75 point 50 just below the lower edge of the press

5. A lower end portion 52 of the conductor section 49 is positioned below the bottom wall of the base 3 and is enclosed by a conducting sleeve 53.

A terminal pin 54 is positioned in the center of the lower end portion 52 of the conducting tube 49 and it is insulated therefrom by means of a sleeve 55. The terminal pin 54 may be extended below the lower end of the tubular portion 52 in order to insure contact with a co-acting socket (not shown). The pin 54 is secured to a section 56 of the lead conductor 9. The section 56 passes up through the center of the tube 47, and it is connected at 57 to a second section 58 of the lead conductor 9 which extends into the press 5. The positioning of the conductor section 56 in the center of the tubular conductor section 47 permits the latter to constitute a magnetic shield, and it also assures that both sections shall be straight throughout their length, thereby preventing the establishment of an unbalanced magnetic field adjacent to the lead conductors 33, 34 and 64.

In order that access may be had to the lower ends of the filament 14, and the upper ends 12 and 13 of the lead conductors 8 and 9, these parts are of such length as to permit the positioning of the lead ends 12 and 13 substantially midway between the stem end portion 11 and the adjacent end of the cathode 29. Such open space permits the ready spot-welding of the conductors 8 and 9 to the filament 14, whereupon said open space may be easily closed by the telescoping sleeves 38 and 42.

Fig. 5 illustrates the connection of the filament 14 of Fig. 1 to a transformer 59 of conventional 110 design. It is noted that a secondary winding 61 of the transformer 59 is connected at a midpoint 62 to ground by means of a conductor 63.

The embodiment of my invention shown in Fig. 4 differs from that of Fig. 1 principally in 115 the grounding of the upper mid-portion 15 of the filament 14 by means of a conductor 64 which extends from the hook 16 through an end wall 65 of a supporting member 66 and the cap 37 of the tubular member 22. The supporting member 120 66, in addition to the end wall 65, is provided with a pair of elongated side wall portions 67 and 68 which closely fit an inner side 69 of the member 22. Thus, the necessity for the insulating members 17 and 23 of Fig. 1 is eliminated, with 125 corresponding simplicity in the construction of the tube. The supporting structure 65, 66 is made of highly magnetic material, thereby adding to the shielding effect of the cathode 29.

The lower ends of the side wall portions 67 and 68 abut against an upper edge portion 71 of an insulating sleeve 72 of lavite or like material. The sleeve 72 is provided with a recess 73 adapted to receive a lower end portion 74 of the tubular member 22, as shown in Fig. 4. The insulating sleeve 72 extends downwardly over an upper end portion 75 of the stem end portion 11 and is provided with an elongated recess 76 adapted to receive a shoulder 77 formed on the stem portion 11.

When the insulating member 72 is moved downwardly into the position shown in dot-and-dash lines in Fig. 4, access is afforded to an open space 78 between the upper end 75 of the stem end portion 11 and the lower end of the tubular member 22, permitting the spot-welding of adjacent end portions 79 and 81 of the conductors 8, 9 and the heating means 14. When it is desired to return the insulating sleeve 72 to its normal position it is moved upwardly into the 130

position of Fig. 4 and then turned slightly, so that the shoulder 77 is not in line with the recess 76.

A conducting sleeve 82 of magnetic material 5 is mounted on the outer side of the insulating sleeve 72 and is connected by means of a conductor 83 with the tubular conductor 22, whereby electrostatic and electromagnetic shielding may be afforded the filament 14 and the lead conductors 8 and 9, as in Fig. 1. The stem end portion 11 may also be provided a sleeve 84 of magnetic material which is in contact with the inner surface thereof. The sleeve 84 is grounded by means of conductor sections 85 and 86 extending 15 to the tubular cathode 29. Here again, the insulating sleeve 72 may be omitted as noted in connection with Fig. 1.

Fig. 6 illustrates the connection of the heating means 14 of Fig. 4 to a transformer 84 and to ground. The structure of Fig. 4 is otherwise as described in connection with Fig. 1.

While I have shown only two embodiments of my invention, for the purpose of describing the same, it is apparent that various modifications 25 may be made therein, without departing from the spirit of my invention.

I claim:

1. A tube having a press provided with a plurality of lead conductors projecting therefrom, 30 heating means connected to said lead conductors, a cathode for at least partially enclosing said heating means, auxiliary means for completely enclosing said lead conductors, and insulating means for positioning said auxiliary means relative to said cathode.

2. A tube provided with a press having a plurality of lead conductors projecting therefrom, 40 heating means connected to some of said lead conductors, a cathode for completely enclosing a portion of said heating means, means for at least partially enclosing said lead conductors, and means extending between said last-mentioned means and said cathode for completely enclosing the point of connection of said cathode and said 45 lead conductors.

3. A tube having a plurality of electrodes including a cathode, a press, conductors extending therefrom, and a plurality of relatively movable metallic telescopic members supported by said 50 press and surrounding some of said conductors, said telescopic members being in direct contact with each other and one of which constitutes the said cathode of the tube.

4. A tube having an anode, cathode and control electrode, and means for heating said cathode 55 provided with lead conductors extending through a press, one of said conductors being positioned co-axially with respect to another throughout their entire length exterior to said press, whereby the fields of said pair of conductors may substantially neutralize.

5. In a tube having an anode, cathode and control electrode, means for heating said cathode 65 provided with a plurality of conductors extending through a press, one of said conductors being of magnetic material and surrounding another of said conductors throughout their entire length exterior to said press so as to constitute a magnetic shield for said other of said conductors.

6. In a vacuum tube having an anode, cathode and control electrode, means for heating said cathode provided with lead conductors extending through a press, one of said conductors substantially 70 enclosing another throughout their entire

length exterior to said press, whereby a non-inductive condition may be maintained.

7. A tube having a press, a base, and conductors extending from said press into said base, one of said conductors surrounding another throughout 80 their entire length exterior to said press, whereby the magnetic field between two of said conductors may be substantially neutralized.

8. The combination in a thermionic vacuum tube having an anode, cathode and control electrode, of a press, conductors extending therefrom, and a plurality of relatively movable telescopic members formed of magnetic material supported by said press and surrounding some of said conductors so as to constitute a magnetic shield 85 therefor, said telescopic members being in direct contact with each other and one of which constitutes the said cathode of the tube.

9. The combination in a thermionic vacuum tube having an anode, cathode and control electrode, of a press, conductors extending therefrom, and a plurality of telescopic members formed of magnetic material supported by a tubular extension 90 of said press and surrounding some of said conductors so as to constitute a magnetic shield 95 therefor, said telescopic members being in direct contact with each other and one of which constitutes the said cathode of the tube.

10. A thermionic vacuum tube having a press, conductors extending from said press, a tubular extension integral with said press and partially enclosing some of said conductors, and a plurality of telescopic members relatively movable with respect to each other and in direct contact with each other supported by said extension.

11. A thermionic vacuum tube having a press, conductors extending from said press, a tubular extension integral with said press and partially enclosing some of said conductors, a plurality of telescopic members in direct contact with each other supported by said extension, and locking means on said extension for locking said telescopic members in desired position thereon.

12. A thermionic vacuum tube having a press, conductors extending from said press, a tubular extension integral with said press and partially enclosing some of said conductors, and a plurality of telescopic members in direct contact with each other supported by said extension, said tubular extension having a magnetic shield positioned 120 therein out of contact with said lead conductors.

13. In a thermionic vacuum tube having an anode, cathode and control electrode, means for heating said cathode, a press, a base and conductors leading from said anode, cathode, control electrode and said heating means and extending from said press into said base, one of the conductors of said heating means surrounding another whereby the magnetic field between the two conductors of said heating means may be substantially neutralized, and a terminal for said heating conductors comprising two coaxial conductor members separated by insulating material, one of said conducting members extending below 135 the other of said members.

14. The combination in a thermionic vacuum tube having an anode, cathode and control electrode, of a press, conductors extending therefrom, and a plurality of relatively movable members formed of magnetic material extending from said press and surrounding some of said conductors so as to constitute a magnetic shield therefor, said members being in direct contact with each other.

15. In a thermionic vacuum tube having an 150

anode, cathode and control electrode, a pair of spaced insulating members carried by said cathode, means supported by said members for heating said cathode, a press, a base and conductors 5 leading from said anode, cathode, control electrode and said heating means and extending from said press into said base, one of the conductors of said heating means surrounding another

(whereby the magnetic field between the two conductors of said heating means may be substantially neutralized), and a terminal for said heating conductors comprising two coaxial conductor members separated by insulating material, one of said conducting members extending below the other of said members. 80
